AU 291 EX

OR D 13,018

DESIGN FOR A FLORAL PEDESTAL.

Design No. 13,018, dated June 27, 1882.

UNITED STATES PATENT OFFICE.

NICHOLAS RAPPLEYEA AND LEO STEIN, OF ROCHESTER, NEW YORK.

DESIGN FOR A FLORAL PEDESTAL.

SPECIFICATION forming part of Design No. 13,018, dated June 27, 1882.

Application filed May 8, 1882. Term of patent 7 years.

To all whom it may concern:

Be it known that we, NICHOLAS RAPPLEYEA and LEO STEIN, both of Rochester, Monroe county, New York, have invented and produced a new and original Design for Floral Pedestals, of which the following is a specification, reference being had to the accompanying photographic illustration, which shows a perspective view of the pedestal.

10 This design relates to pedestals or supports for holding flowers and floral offerings at funerals, &c.

The design consists of a tall molded or beaded column with central moldings of ornamental 15 form, and tufted surfaces above and below the central moldings, whereby a highly ornamental and pleasing effect is produced.

In the illustration, *a* is the plinth; *b*, the moldings at the bottom of the column. *c* is 20 the abacus, and *d* the moldings at the top of the column. *f* are ornamental moldings in the center of the column, and *g g* are two tufted surfaces covering the cylindrical portions of

the column above and below the central moldings.

By the means above described the tall pedestal presents the appearance of a double column, one above the other, and produces a highly-ornamental effect, the two tufted surfaces relieving the monotony of the long cylindrical portions of the column.

What we claim as new is—

The design for a floral pedestal, consisting of a beaded column with moldings in the center of the column and tufted surfaces above 35 and below the central moldings, as shown and described.

In witness whereof we have hereunto signed our names in the presence of two subscribing witnesses.

NICHOLAS RAPPLEYEA.
LEO STEIN.
